Primary Examiner — Marianne N Pandozzi*Assistant Examiner* — Jae Liang(74) *Attorney, Agent, or Firm* — Armstrong Teasdale LLP(57) **CLAIM**

I claim the ornamental design for a vent insert for a drinking container, as shown and described.

DESCRIPTION

FIG. 1 is a perspective view of a vent insert for a drinking container showing our new design;

FIG. 2 is a right side elevational view thereof;

FIG. 3 is a left side elevational view thereof;

FIG. 4 is a front elevational view thereof;

FIG. 5 is a rear elevational view thereof;

FIG. 6 is a top plan view thereof; and,

FIG. 7 is a bottom plan thereof.
